ILLUMINATED SIGN

Harry J. Cudney, Buffalo, N. Y., assignor to Flex-lume Corporation, Tonawanda, N. Y., a corporation of New York

Application April 16, 1932, Serial No. 605,763

19 Claims. (Cl. 40—130)

This application is a continuation in part of and a substitute for my co-pending application Serial No. 587,032, filed January 16, 1932, for Illuminated signs.

- 5 This invention relates to improvements in signs of the kind wherein the display characters are illuminated by electroluminescent tubes which outline the area within which the display characters are arranged and more particularly 10 the invention is concerned with such a sign in which the display characters are interchangeable in order that the matter displayed may be varied at will.
- 15 A sign of the type generally described is of the so-called indoor type and in the use of such a sign it is the practice to suspend or support the sign in a display window in close proximity to a glass panel thereof so that it will attract the attention of passers-by.
- 20 The electroluminescent tubes are connected to suitable transformers which are adapted to provide current of the necessary voltage, the transformers being preferably located at a remote point in order to avoid detracting from the appearance of the sign or the window.

The principal object of the invention is to provide for facility in interchanging the display characters, this object contemplating a construction in which the display characters are accessible from the rear of the sign, thereby enabling interchanging of the display characters from the rear of the sign when access to the display characters cannot be conveniently had from the front of the sign without disturbing its position.

35 A further object is to provide for the support of the sign in such a manner that the display characters may be presented in the desired plane.

A still further object is a novel arrangement of the parts of the sign whereby simplicity in construction and in the assembly of the parts is obtained.

A still further object is to provide a novel means of support for the display characters whereby the latter when illuminated appear from a short distance to be suspended in space without any visible means of support.

The invention is illustrated in the accompanying drawing in which:

50 Figure 1 is a front elevation of a sign constructed in accordance with the invention.

Figure 2 is a top plan view of the sign, the latter being shown arranged behind the glass panel of a display or show window.

55 Figure 3 is an enlarged end elevation of the sign.

Figure 4 is an enlarged section taken along line 4—4 of Figure 1.

Figure 5 is a detail section taken along line 5—5 of Figure 3.

Figure 6 is an enlarged detail section taken along line 6—6 of Figure 1.

Figure 7 is a detail section through one of the supporting rods and is taken along line 7—7 of Figure 1.

The sign, as illustrated, includes a frame 8 which is adapted to carry the display characters 9. The said frame may be of any suitable construction. As shown, it includes horizontal rods 10 which are connected at their ends to and supported in the desired spaced relation by end bars 11. The rods 10 are preferably arranged in pairs, there being one pair of rods for each row of display characters. The distance between adjacent pairs of the rods may be varied to meet different requirements. It is preferred that the rods 10 be provided with surfaces of high light absorptive characteristics. For example, if the rods in their natural condition do not have such characteristics they may be coated with a dull black lacquer, as indicated at 10a (Figure 7). It is understood that the size of the rods will depend upon the work that they have to perform. When they are of the character described that portion of the light which in the illumination of the display characters strikes them is absorbed. Hence the reflected light is solely from the display characters and the latter, therefore, appear from a short distance to be suspended in space without any visible means of support. This adds materially to the appearance of the signs as well as arousing the interest of observers.

The display characters are preferably supported from the upper rod of each pair of rods, the lower rods of the pairs serving to hold the display characters in a common plane. The display characters, therefore, carry hooks 12 upon their rear sides which fit over the upper rod 10 of the pairs of rods.

In order to add to the attractive appearance of the sign, the display characters are preferably arranged in front of a contrasting background. The latter is provided in any suitable manner upon a sheet 13 of any desired material. The sheet 13 is supported by suitable hooks 14 which are carried by the sheet 13 and which fit over the upper rod 10 of the upper pair of rods. The sheet 13 is thus supported behind the display characters 9 which appear in relief relative to the background. The sheet 13, and hence the background, may be detached from the sign by

lifting it slightly to disengage the hooks 14 from the supporting rod.

The illumination of the display characters, in the embodiment illustrated, is effected by an electroluminescent tube 15 which is bent to follow in outline the margins of the background sheet, the electrode carrying portions 16 of the tube terminating above one of the upper corners of the background sheet. The electrodes of the tube may be connected by lead wires 16a to suitable transformers which are adapted to supply a current of the necessary voltage to the tube. The tube is supported in the position described by a pair of arms 17 which are secured at the opposite upper corners of the frame 8 against the end bars 11. The securing of the arms 17 may be conveniently effected by mounting the arms upon the ends of the upper rod 10 of the upper pair of rods. The arms 17, as best shown in Figures 3 and 4, are formed at their outer ends to provide open rings 18 which resiliently engage the tube and support the latter in the desired position. The rings 18 enable the tube to be secured to the arm 17 quickly and without the necessity of tools. The rings also enable convenient removal of the tube when occasion may require, for example, when it is necessary to refill the tube or to replace the latter.

The arms 17 are availed of in connection with wires 19 in the support of the sign. The connection between the bars 17 and the wires 19 is preferably effected through the agency of clips 20. The latter frictionally engage the sides of the bars 17 but are slidable along the latter between the rings 18 and the frame 8. The wires 19 are adapted for connection to convenient overhead structure and are of such a length as to suspend the sign at the desired height. The clips 20 are adapted for movement along the bars 17 so that the sign may be balanced in such a position that the display characters are presented in the desired plane. The clips, therefore, are available to initially balance the sign as well as to compensate for any overbalance which may subsequently result because of the rearrangement or replacement of the display characters, the electroluminescent tube, or other parts of the sign.

A sign of the type generally described is commonly referred to as an indoor sign and its principal use is in connection with display or show windows. When employed in this connection, the sign is usually supported a short distance behind the glass panel of the window in order that it will attract the attention of passersby. The sign is illustrated in this connection in Figures 2 and 3 in which the display or show window is sufficiently illustrated by a showing of one of the glass panels 21 thereof. When employed in the manner illustrated, it is preferred that when the sign is once arranged in the position desired that there be no necessity for further movement or change in position of the sign, this being desirable in order to prevent disturbance of the lead-wires 16a by which the current is supplied to the tube and to avoid injury to the tube. It will be apparent, therefore, that the permanency of the position of the sign cannot be attained where access to the display characters may be had only from the front of the sign, the glass panel 21 of the display or show window preventing convenient access to the display characters from this side of the sign.

From the foregoing, it will be apparent that the present invention contemplates a construc-

tion in which interchangeable display characters are employed and in which the interchanging of the display characters may be conveniently effected, when the sign is once arranged in the desired position, without the necessity of disturbing the position of the sign or the lead wires to the electroluminescent tube. When it is desired to vary the matter displayed, the sheet 13 which provides the background for the characters is lifted slightly to disengage the hooks 12 from the rod which carries the sheet. The display characters 9 are thus rendered accessible from the rear of the sign and they may be interchanged at will.

It will be apparent that the sign has characteristics which render it highly desirable for advertising purposes. The display characters employed in connection with the sign may be in sets, the characters of each set having different characteristics as, for example, color or style. There may also be a number of backgrounds having different characteristics adapted to be employed in connection with the sets of display characters, thereby providing a wide variety of contrasting effects. If desired the sign may be employed without the use of a background, this use of the sign having the advantage that a considerable portion of the interior of the window behind the sign is visible through the latter.

I claim as my invention:

1. In a sign having interchangeable display characters, the combination of a frame including means by which the said characters are supported in the desired arrangement and an electroluminescent tube outlining the area within which the said characters are arranged and adapted to illuminate said characters, said tube being supported by and in front of said means, said means being formed to enable access to said characters from the rear of the sign, whereby the interchanging of the display characters may be effected from the rear of the sign when access to the display characters from the front of the sign cannot be conveniently had without disturbing the position of the sign, said means having high light absorptive characteristics so that from a short distance the said display characters appear to be suspended in space without any visible means of support.

2. In a sign having interchangeable display characters, the combination of a frame including horizontal spaced elements by which the display characters are supported in the desired arrangement and an electroluminescent tube outlining the area within which the display characters are arranged and adapted to illuminate said characters, said tube being supported by and in front of said frame, the spacing between said elements being sufficient to enable access to said characters from the rear of the sign, whereby the interchanging of the display characters may be effected from the rear of the sign when access to the display characters from the front of the sign cannot be conveniently had without disturbing the position of the sign, said elements having high light absorptive characteristics so that from a short distance the said display characters appear to be suspended in space without visible means of support.

3. In a sign having interchangeable display characters, the combination of a frame including horizontal spaced elements by which the display characters are supported in the desired arrangement, an electroluminescent tube outlining the area within which the display characters are arranged and adapted to illuminate said characters

- and arms carried by said frame by which said tube is supported in front of said display characters, the spaces between said elements being sufficient to enable access to said characters from the rear of the sign, whereby the interchanging of the display characters may be effected from the rear of the sign when access to the display characters from the front of the sign cannot be conveniently had without disturbing the position of the sign, said elements having high light absorptive characteristics so that from a short distance the said characters appear to be suspended in space without any visible means of support.
4. In a sign having interchangeable display characters, the combination of a frame including means by which the display characters are supported in the desired arrangement, an electroluminescent tube outlining the area within which the said characters are arranged and adapted to illuminate the said characters and arms carried by said frame and by which said tube is supported in front of the said display characters, said means being formed to enable access to said characters from the rear of the sign, whereby the interchanging of the display characters may be effected from the rear of the sign when access to the display characters from the front of the sign cannot be conveniently had without disturbing the position of the sign, said means having high light absorptive characteristics so that from a short distance the said display characters appear to be suspended in space without any visible means of support.
5. In a sign having interchangeable display characters, the combination of a frame by which the display characters are supported in the desired arrangement, an electroluminescent tube outlining the area within which the said characters are arranged and adapted to illuminate the said characters, arms carried by said frame by which said tube is supported in front of said display characters and clips carried by said arms and by which the sign may be suspended, said clips being slideable along said arms to balance the sign so that the display characters are presented in the desired plane, said frame being formed to enable access to said characters from the rear of the sign, whereby the interchanging of the display characters may be effected from the rear of the sign when access to the display characters from the front of the sign cannot be conveniently had without disturbing the position of the sign.
6. In a sign having interchangeable display characters, the combination of a frame by which the display characters are supported in the desired arrangement, an electroluminescent tube outlining the area within which the said characters are arranged and adapted to illuminate the said characters and arms carried by said frame by which said tube is supported in front of said characters, said arms being formed to resiliently engage said tube so that it may be readily attached to and detached from the sign, said frame being formed to enable access to said characters from the rear of the sign, whereby the interchanging of the display characters may be effected from the rear of the sign when access to the display characters from the front of the sign cannot be conveniently had without disturbing the position of the sign.
7. In a sign having interchangeable display characters, the combination of a frame by which the said characters are supported in the desired arrangement, an electroluminescent tube outlining the area within which the said characters are arranged and adapted to illuminate said characters, said tube being supported by and in front of said frame, and a background carried by said frame behind said display characters, said background being detachably carried by said frame, whereby it may be removed to enable access to said display characters from the rear of the sign so that the interchanging of the display characters may be effected from the rear of the sign when access to the display characters from the front of the sign cannot be conveniently had without disturbing the position of the sign.
8. In a sign having interchangeable display characters, the combination of a frame by which the said characters are supported in the desired arrangement, an electroluminescent tube outlining the area within which the said characters are arranged and adapted to illuminate said characters, said tube being supported by and in front of said frame and a background carried by said frame behind said display characters, said background being detachably carried by said frame, whereby it may be removed to enable access to said display characters from the rear of the sign so that the interchanging of the display characters may be effected from the rear of the sign when access to the front of the sign cannot be conveniently had without disturbing the position of the sign.
9. In a sign having interchangeable display characters, the combination of a frame including horizontal rods by which the display characters are supported in the desired arrangement, an electroluminescent tube outlining the area within which the display characters are arranged and adapted to illuminate said characters, said tube being supported by and in front of said frame, and a background carried by said frame behind said display characters, said background being detachably carried by said frame, whereby it may be removed to enable access to said display characters from the rear of the sign so that the interchanging of the display characters may be effected from the rear of the sign when access to the display characters from the front of the sign cannot be conveniently had without disturbing the position of the sign.
10. In a sign having interchangeable display characters, the combination of a frame including horizontal rods by which the display characters are supported in the desired arrangement, an electroluminescent tube outlining the area within which the display characters are arranged and adapted to illuminate said characters, said tube being supported by and in front of said frame, a background provided by a sheet of suitable material and hooks carried by said sheet for cooperating with one of said rods to detachably secure said sheet to said frame, whereby said sheet may be removed to enable access to said display characters from the rear of the sign so that the interchanging of the display characters may be effected from the rear of the sign when access to the display characters from the front of the sign cannot be conveniently had without disturbing the position of the sign.
11. In a sign having interchangeable display characters, the combination of a frame including horizontal rods by which the display characters are supported in the desired arrangement, an electroluminescent tube outlining the area within which the display characters are arranged and adapted to illuminate said characters, said tube being supported by and in front of said frame, and a background carried by said frame behind said display characters, whereby it may be removed to enable access to said display characters from the rear of the sign so that the interchanging of the display characters may be effected from the rear of the sign when access to the display characters from the front of the sign cannot be conveniently had without disturbing the position of the sign.

- which the display characters are arranged and adapted to illuminate said characters, arms carried by said frame by which said tube is supported in front of said display characters and a background arranged behind said display characters, said background being detachably secured to said frame, whereby it may be removed to enable access to said display characters from the rear of the sign so that interchanging of the display characters may be effected from the rear of the sign when access to the display characters from the front of the sign cannot be conveniently had without disturbing the position of the sign.
12. In a sign having interchangeable display characters, the combination of a frame including horizontal rods by which the display characters are supported in the desired arrangement, an electroluminescent tube outlining the area within which the display characters are arranged and adapted to illuminate said characters, arms carried by said frame by which said tube is supported in front of said display characters, a background arranged behind said display characters and hooks co-operating with one of said rods for detachably securing said background to said frame, whereby it may be removed to enable access to said display characters from the rear of the sign so that interchanging of the display characters may be effected from the rear of the sign when access to the display characters from the front of the sign cannot be conveniently had without disturbing the position of the sign.
13. In a sign having interchangeable display characters, the combination of a frame including horizontal rods by which the display characters are supported in the desired arrangement, an electroluminescent tube outlining the area within which the display characters are arranged and adapted to illuminate said characters, arms carried by said frame by which said tube is supported in front of said display characters, said arms being formed to resiliently engage said tube whereby its attachment to and detachment from the sign is facilitated, said arms also being utilized in the support of the sign, a sheet of suitable material arranged behind said display characters and adapted to provide a background therefor and hooks carried by said sheet and co-operating with one of said rods for detachably securing said sheet to said frame, whereby it may be removed to enable access to said display characters from the rear of said sign so that interchanging of said display characters may be effected from the rear of the sign when access to the display characters from the front of the sign cannot be conveniently had without disturbing the position of the sign.
14. In a sign having interchangeable display characters, the combination of a frame by which the display characters are supported in the desired arrangement, an electroluminescent tube outlining the area within which the said characters are arranged and adapted to illuminate the said characters, arms carried by said frame by which said tube is supported in front of said display characters and a background carried by said frame behind said display characters, said background being detachably secured to said frame, whereby it may be removed to enable access to the display characters from the rear of the sign so that interchanging of the display characters may be effected from the rear of the sign when access to said characters from the front of the sign cannot be conveniently had without disturbing the position of the sign.
15. In a sign having interchangeable display characters, the combination of a frame by which the display characters are supported in the desired arrangement, an electroluminescent tube outlining the area within which the display characters are arranged and adapted to illuminate said characters, arms carried by said frame and by which said tube is supported in front of said display characters, said arms being formed to resiliently engage said tube so that its attachment to and detachment from the said frame is facilitated and a background carried by said frame behind said display characters, said background being detachably secured to said frame, whereby it may be removed to enable access to said display characters from the rear of the sign so that interchanging of the display characters may be effected from the rear of the sign when access to said characters from the front of the sign cannot be conveniently had without disturbing the position of the sign.
16. In a sign having interchangeable display characters, the combination of a frame by which the display characters are supported in the desired arrangement, an electroluminescent tube outlining the area within which the display characters are arranged and adapted to illuminate said display character, arms carried by said frame by which said tube is supported in front of said display characters, clips carried by said arms and by which the sign may be suspended, said clips being slidable along said arms to balance the sign so that the display characters are presented in the desired plane and a sheet of suitable material arranged behind said display characters and adapted to provide a background therefor, said sheet being detachably secured to said frame, whereby it may be removed to enable access to said display characters from the rear of the sign so that interchanging of the display characters may be effected from the rear of the sign when access to said display characters from the front of the sign cannot be conveniently had without disturbing the position of the sign.
17. In a sign having interchangeable display characters, the combination of a frame including means by which the said characters are supported in the desired arrangement and an electroluminescent tube outlining the area within which the said characters are arranged and adapted to illuminate said characters, said electroluminescent tube being supported by and in front of said frame, said means being formed to enable access to said characters from the rear of the sign, whereby the interchanging of the display characters may be effected from the rear of the sign when access to the display characters from the front of the sign cannot be conveniently had without disturbing the position of the sign, said means having characteristics such that from a distance the said display characters appear to be suspended in space without any visible means of support.
18. In a sign having interchangeable display characters, the combination of a background, means for supporting said characters in front of and in spaced relation with respect to said background, said means being adapted to accommodate various numbers and arrangements of said characters, an electroluminescent tube outlining the area within which said characters are arranged and adapted to illuminate said characters, forwardly extending arms for supporting said tube in a plane in front of the plane occupied by said display characters, said tube being

5 detachably connected to the outer ends of said arms, said first mentioned supporting means having high light absorptive characteristics so that the exposed areas thereof do not, to an appreciable degree, act as light reflecting surfaces, whereby from a short distance said characters appear to be suspended in space without visible means of support.

19. In a sign having interchangeable display characters, the combination of a back ground, means for supporting said characters in front of and in spaced relation with respect to said background, said means being adapted to accommodate various numbers and arrangements of said

15 characters, an electroluminescent tube outlining

the area within which said characters are arranged and adapted to illuminate said characters and forwardly extending arms for supporting said tube in a plane in front of the plane occupied by said characters, the outer ends of said arms being formed to resiliently engage said tube so as to detachably secure it in the desired relation with respect to said characters, said supporting means having high light absorptive characteristics so that the exposed areas thereof do not, to an appreciable extent, act as light reflecting surfaces, whereby from a short distance said characters appear to be suspended in space without visible means of support.
